UNITED STATES PATENT OFFICE.

ENOCH V. STODDARD, OF ROCHESTER, NEW YORK.

DIRECTORY FOR COMMERCIAL BUILDINGS AND APARTMENT-HOUSES.

935,704.

Specification of Letters Patent.

Patented Oct. 5, 1909.

Application filed November 6, 1908. Serial No. 461,410.

To all whom it may concern:

Be it known that I, ENOCH V. STODDARD, a citizen of the United States, and resident of Rochester, in the county of Monroe and State 5 of New York, have invented certain new and useful Improvements in Directories for Commercial Buildings and Apartment-Houses, of which the following is a specification.

This invention relates to directories for 10 commercial buildings and apartment houses, and its object is to provide one that can be expanded, or rearranged to meet different requirements and changing conditions. To this end it is built up of separable units that 15 can be joined to build up as large a directory as required, when it is set up in the first instance, or subsequently to meet new requirements, for the inclosing frame is adapted to be extended to accommodate any number of 20 name-plate panels.

Other novel features of the invention are found in the means for removably supporting the name-plates within the panels.

In the drawings:—Figure 1 is a front elevation of one panel or “unit” of the frame; Fig. 2 is its central vertical section; Fig. 3 is its horizontal section; Fig. 4 is a view similar to Fig. 3, but showing a name-plate partially removed; Fig. 5 is a perspective view 25 of a name-plate; Fig. 6 is a front view of a two-panel frame, with the panels and doors in place; Fig. 6^a is part of a vertical section through the center of one of the panels of Fig. 6, showing the panel in its place in the 30 lower rail; Fig. 7 is a horizontal cross-section of the same; Fig. 8 is a perspective view of one of the corner-blocks of the frame; Fig. 9 is a partial perspective view of the 35 top-rail of the frame; and Fig. 10 is a partial perspective view of the end-stile.

One of the units, or panels, of the directory is shown apart from the frame in Figs. 1-4, inclusive, of the drawings. Referring to these figures, it is seen that the sides, or 40 stiles, of the panel each has a tongue 3 on the outer edge, that the top piece 4 also has a tongue 3^a on its edge, and that the bottom piece 5 has a recess 3^b. Instead of the recess 3^b in the bottom piece 5 there may be a tongue 3^a, as represented in Fig. 6^a, when 45 the directory is designed for horizontal extension only, or is only one panel long. Referring still to the panel shown most clearly in Figs. 1-4, inclusive, one of the stiles 2, for 50 example, has a rabbet 6 its whole length, and in the back thereof a number of slots 7,

which serve to hold the name plates 8 in place. These name plates (see Fig. 5) are each straight, flat pieces of a material that is suitable, and are, respectively, tapered down 60 at one end, where a lug 9 is located that is adapted to enter the slots 7, whereas their opposite ends are, respectively, adapted to enter the recesses 10 in the stile 1, where each lies against a projecting rib 11. The ends 65 of the plates 8 that carry the lugs 9 are held within the stile 2 by an overlapping piece 12, that is hinged to it, and adapted to fold down upon it. When a name plate is to be removed from the panel, the piece 12 is 70 swung outwardly, as shown in Fig. 4, till it uncovers the tapered ends of the name plates. When one or more name plates have been removed, those remaining are held in place by 75 the lugs 9 within the slots 7.

A glass door 13 may, if desired, be hinged to the head piece 4 of each panel, and both the head and bottom pieces of the door bevelled on their inner face so that it closes tightly against said pieces, as shown in Fig. 80 2. In Figs. 1, 3 and 4, the door 13 is omitted in order that the position of the name plates may be seen clearly.

The frame which is adapted to contain one or more of the panels just described is 85 shown in Figs. 6 to 10, inclusive. It comprises corner blocks 14 that are mortised and dovetailed to the top and bottom pieces, as shown in Figs. 8 to 10, inclusive. These Figs. 8, 9 and 10 are so grouped in the drawings that they illustrate the manner in which both the top and bottom rails 16 and the side rails 15 are joined with the corner piece 14, since they are shown in these figures in their proper relative positions and only sufficiently withdrawn from each other to show the construction of each.

The side rails 15 of the containing frame have recesses 17 in their inner faces, to receive the tongues 3 that project from the 100 sides of the panels previously described, and the top and bottom rails 16 of the frame are also recessed at 18 to receive the tongues 3^a (see Fig. 9). The doors 13, previously described, are held down upon the frame by 105 suitable means, as latches 19.

The frame is readily expandible in either a vertical or horizontal direction to receive additional panels. When expanded horizontally, top and bottom rails 16^a are used, 110 which are mortised and dovetailed at both ends in the manner shown in Fig. 9 with

respect to one end of a rail 16, by way of illustration. It should be noted that the ends of rails 16 are so mortised that they respectively fit the corner piece 14, when the directory is one section in width, and that the rails 16^a are each mortised at one end to fit one end of any of the rails 16, and at its other end to fit a corner piece 14, (see Fig. 6.)

10 It is obvious that if the directory is to be wider than the two sections shown in Fig. 6, all that need be done is to insert between the corner pieces 14 at the left of Fig. 6 and the top and bottom rails 16^a additional rails 15, and place a panel within the extension of the frame. It is also obvious that when the frame is to be extended vertically, all that needs be done is to insert, on each side, a rail that is mortised at each end to correspond, respectively, with the mortised ends of the rails 16^a, and is equal in length to the length of the panel.

15 In order to adapt a panel for both horizontal and vertical extension, its lower end should be recessed, as shown by 3^b in Fig. 2, in which case the recess will receive the tongue 3^a on the other section when one section is mounted on the other. If such a section is used alone, or alongside another, the 20 tongue 3^a on its top rail and the tongues 3 on its side rails are sufficient to hold the section within the frame.

25 When the directory is extended horizontally a secondary tongue 3^c on one end of the tongues 3 enters a corresponding recess 3^d in the adjacent tongue 3 of the next section. As each section is provided with a secondary

30 tongue and recess on the same side, respectively, this feature is also adapted for horizontal extension.

35 The whole structure is supported from the wall on suitable brackets, or rests upon the floor.

40 What I claim is:—

45 1. An expandible frame for a building directory and like purposes, comprising corner pieces 14; corresponding top and bottom rails 16; corresponding side rails 15; and corresponding pieces for extension 16^a; the said corner pieces being mortised; the said 50 top, bottom and side rails being mortised to correspond therewith; and the said extension pieces being mortised to fit between corner pieces on the same side of the frame and the rails aforesaid; and means for securing together adjacent parts of the frame.

55 2. An expandible building directory, comprising a plurality of similar name plate sections or panels, adapted to lie side by side for horizontal extension, said sections or 60 panels having means for retaining them together or end to end for vertical extension and adapted to receive and hold one of said sections, or several of them, both in horizontal and in vertical extension, comprising corner 65 pieces, top, bottom, side rails and extension pieces, corresponding with the dimensions of said sections, all mortised to fit one another in position; substantially as shown and described.

ENOCH V. STODDARD.
